Bridgeport, Wash.

Application November 14, 1958, Serial No. 773,860

5 Claims. (Cl. 240—8.2)

This invention relates in general to new and useful improvements in electrical connections, and more specifically to an improved electrical connection for light bulbs.

In the construction of lights for automobiles, boats, etc., one of the main problems encountered is providing a complete seal against the entrance of dirt, water or other foreign matter. Although the lens may be easily sealed to the housing of the light, at least one opening must be made in the housing for the passage of the wire to the bulb. It is through this opening that foreign matter enters into the light housing.

It is therefore the primary object of this invention to provide an electrical connection between a wire and a bulb of a light wherein the opening through the housing of the light through which the wire passes is sealed against the entrance of foreign matter.

Another object of this invention is to provide an improved electrical connection between an electric wire and a light bulb, the connection including a socket which has adjustably positioned therein a bulb holder, and sealing washers in the socket which are compressible upon the positioning of a bulb in the bulb holder so as to form a seal between the wire for the bulb and the socket.

A further object of this invention is to provide an improved light which includes a metal housing having projecting through a wall thereof a socket, means carried by the socket for mounting a bulb and for sealing the connection between a wire and the bulb at its source of entry into the socket, and a lens sealed to the housing to form a completely sealed unit.

A further object of this invention is to provide an improved sealed connection between a light bulb and a wire, the connection including a socket and resilient sealing washers which are compressed by a bulb holder so as to tightly seal the wire for the bulb relative to the socket.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a fragmentary perspective view of a vehicle on which there is mounted a light constructed in accordance with this invention;

Figure 2 is an enlarged fragmentary sectional view taken substantially upon the plane indicated by the section line 2—2 of Figure 1 and shows the specific relationship of the light with respect to the vehicle as well as the details of the light;

Figure 3 is an enlarged fragmentary sectional view taken substantially upon the plane indicated by the section line 3—3 of Figure 2 and shows further the specific details of the construction of the light; and

Figure 4 is an enlarged fragmentary sectional view taken substantially upon the plane indicated by the section line 4—4 of Figure 3 and shows the specific details of a ground connection in the light.

Referring now to the drawings in detail, it will be seen that there is illustrated in Figure 1 a portion of a vehicle which is referred to in general by the reference numeral 10. The vehicle, among other components, includes a wall 12 on which there is mounted the light which is the subject of this invention, the light being referred to in general by the reference numeral 14.

2

The light 14 includes a housing which is referred to in general by the reference numeral 16. The housing 16 is formed of metal and includes a rear wall 18, an outwardly projecting upper wall 20 and a lower wall 22.

5 The housing 16 is generally channel-shaped in cross-section and the walls 20 and 22 are generally semi-circular in plan.

Carried by the rear wall 18 of the housing 16 is a socket which is referred to in general by the reference numeral 24. The socket 24 includes a sleeve portion 26 which is provided at the forward end thereof with an annular flange 28 and at the rear end thereof with an end wall 30. The sleeve portion 26 extends through aligned openings 32 and 34 in the rear wall 18 and the vehicle wall 12, respectively. Flange 28 is disposed in abutting engagement with the forward surface of the rear wall 18 and is suitably secured thereto in watertight relation. The rear wall 30 is provided with a wire receiving opening 36 therethrough.

10 Removably carried by the socket 24 is a bulb holder which is referred to in general by the reference numeral 38. The bulb holder 38 includes an outer externally threaded sleeve 40 which is threadededly engaged with an internally threaded forward portion 42 of the sleeve portion 26. The outer portion 40 has a pair of outwardly extending fingers 44 to facilitate the turning thereof with respect to the socket 24.

15 Removably carried by the socket 24 is a bulb holder which is referred to in general by the reference numeral 38. The bulb holder 38 includes an outer externally threaded sleeve 40 which is threadededly engaged with an internally threaded forward portion 42 of the sleeve portion 26. The outer portion 40 has a pair of outwardly extending fingers 44 to facilitate the turning thereof with respect to the socket 24.

20 The bulb holder 38 also includes a bulb connecting member 46. The bulb connecting member 46 is illustrated

25 as being of the bayonet type and receives a bayonet type bulb 48. However, the bulb securing member 46 may be of any type, and if desired, may be internally threaded for receiving a screw threaded type of bulb.

25 In order that electrical current may be supplied to the bulb 48, there is provided a lead wire which is referred to in general by the reference numeral 50. The lead wire 50 includes a conductor 52 having insulation 54.

30 The opening 36 is of a diameter substantially equal to the diameter of the insulation 54. The conductor 52 extends beyond the insulation 54 and terminates in a contact 56. Carried by the conductor 52 immediately rearwardly of the contact 56 is an insulating disc 58. Also carried by the conductor 52 is a compressible resilient sealing washer 60. The sealing washer 60 is disposed intermediate the insulating disc 58 and the end wall 30 of the socket.

35 When the bulb 48 is properly positioned in the bulb holder 38, a contact 62 of the bulb 48 projects rearwardly of the bulb securing member 46 for engagement with the contact 56.

40 Disposed intermediate the base of the bulb 48 and the insulating disc 58 is a second sealing washer 64. The sealing washer 64 is also formed of a resilient material and is thicker than the washer 60. The sealing washer 55 64 has a central bore 66 therethrough through which the contacts 56 and 62 extend.

45 In order to assure the sealing of the connection between the wire 50, the socket 24 and the bulb 48, the bulb 48 is first mounted in the bulb holder 38. The bulb holder

50 38 is then screwed into the socket 24 until the base of the bulb 48 compressively engages the sealing washer 64.

55 The sealing washer 64 is compressed until the contacts 56 and 62 engage each other. At the same time, the pressure applied both on the sealing washer 64 and on the contact 56 urges the insulating disc 58 rearwardly so as to compress the sealing washer 60 between the insulating disc 58 and the rear wall 30 of the socket 24. This in effect provides a double seal and the entrance of foreign 60 matter into the socket 24 beyond the sealing washers 60 and 64.

In order that the circuit to the bulb 48 may be completed, there is provided a ground wire 66 which includes a conductor 68 and an insulation 70. Secured to the underside of the bottom wall 22 of the light housing 16 is a fitting 72 having at least one transverse bore 74 therethrough. Threadedly positioned in a bore 76 which intersects the transverse bore 74 is a setscrew 78. In practice, insulation is stripped from an end of the wire 66 to expose a short length of the conductor 68. The insulated portion of the wire 66 is then passed into the bore 74 until the conductor 68 has the exposed portion thereof alined with the setscrew 78. The setscrew 78 is then tightened down to both clamp the conductor 66 in place and to form an electrical connection between the conductor 68 thereof and the light housing 16 which is formed of metal. Inasmuch as the wire 66 is the ground wire, it will be seen that the light housing 16, the socket 24 and the bulb holder 38 are all grounded.

The light 14 also includes an arcuate lens 80 which is sealed relative to the rear wall 18 by means of a gasket 82. The lens 80 is held in place by a plurality of metal strips 84 which have end portions 86 secured in place by bolts 88. It is to be noted that the end portions 86 are so arranged with respect to the rear wall 18 whereby the metal strips 84 may be tensioned.

Certain of the strips 84 are disposed along the upper and lower edges of the lens 80 to form a shield between the lens 80 and the top and bottom walls 20 and 22, respectively. This seal is in addition to the seal formed between the lens 80 and the light housing 16 by the gasket 82.

As is best illustrated in Figure 2, the fasteners 88 which serve to secure the strips 84 in place also pass through the wall 12 of the vehicle 10 and may serve to secure the light 14 in place. However, other suitable securing means may be used if desired.

From the foregoing, it will be readily apparent that there has been devised an electrical connection between a light bulb and a lead wire therefor which is sealed completely so as to prevent entrance of foreign matter into a bulb socket adjacent the bulb. Furthermore, the housing and lens of the light are so sealed relative to each other whereby a completely sealed unit is provided. In addition to these desirable features of the present invention, it will also be readily apparent that the light 14 is of an extremely simple construction so that the manufacture thereof is economically feasible and at the same time the light 14 may be easily mounted.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. An electrical connection for light bulbs comprising a socket having an end wall, a wire opening through said end wall, a wire extending into said socket through said wire opening, a contact on an end of said wire within said socket, an insulated disc on said wire immediately adjacent said contact, a first sealing washer on said wire intermediate said insulated disc and said end wall, a tubular bulb holder, said bulb holder having open ends and bulb securing means mounted therein for positioning a bulb in said bulb holder with a contact of the bulb projecting through one end thereof, cooperating thread means on said bulb holder and said socket for positioning said bulb holder in said socket, and a second sealing washer disposed intermediate said insulated disc and said bulb holder.

2. An electrical connection for light bulbs comprising a socket having an end wall, a wire opening through said end wall, a wire extending into said socket through said

wire opening, a contact on an end of said wire within said socket, an insulated disc on said wire immediately adjacent said contact, a first sealing washer on said wire intermediate said insulated disc and said end wall, a tubular bulb holder, said bulb holder having open ends and bulb securing means mounted therein for positioning a bulb in said bulb holder with a contact of the bulb projecting through one end thereof, cooperating thread means on said bulb holder and said socket for positioning said bulb holder in said socket, and a second sealing washer disposed intermediate said insulated disc and said bulb holder, said second sealing washer having a normal thickness greater than the combine lengths of said wire contact and the projecting portion of the bulb contact.

3. An electrical connection for light bulbs comprising a socket having an end wall, a wire opening through said end wall, a wire extending into said socket through said wire opening, a contact on an end of said wire within said socket, an insulated disc on said wire immediately adjacent said contact, a first sealing washer on said wire intermediate said insulated disc and said end wall, a tubular bulb holder, said bulb holder having open ends and bulb securing means mounted therein for positioning a bulb in said bulb holder with a contact of the bulb projecting through one end thereof, cooperating thread means on said bulb holder and said socket for positioning said bulb holder in said socket, and a second sealing washer disposed intermediate said insulated disc and said bulb holder, said second sealing washer having a normal thickness greater than the combine lengths of said wire contact and the projecting portion of the bulb contact.

4. An electrical connection for light bulbs comprising a socket having an end wall, a wire opening through said end wall, a wire extending into said socket through said wire opening, a contact on an end of said wire within said socket, an insulated disc on said wire immediately adjacent said contact, a first sealing washer on said wire intermediate said insulated disc and said end wall, a tubular bulb holder, said bulb holder having open ends and bulb securing means mounted therein for positioning a bulb in said bulb holder with a contact of the bulb projecting through one end thereof, cooperating thread means on said bulb holder and said socket for positioning said bulb holder in said socket, and a second sealing washer disposed intermediate said insulated disc and said bulb holder, said bulb securing means being of the bayonet type.

5. An electrical connection for light bulbs comprising a socket having an end wall, a wire opening through said end wall, a wire extending into said socket through said wire opening, a contact on an end of said wire within said socket, an insulated disc on said wire immediately adjacent said contact, a first sealing washer on said wire intermediate said insulated disc and said end wall, a tubular bulb holder, said bulb holder having open ends and bulb securing means mounted therein for positioning a bulb in said bulb holder with a contact of the bulb projecting through one end thereof, cooperating thread means on said bulb holder and said socket for positioning said bulb holder in said socket, and a second sealing washer disposed intermediate said insulated disc and said bulb holder, said socket being a sealed part of a metal light housing, a ground wire connecting on said light housing.

5. An electrical connection for light bulbs comprising a socket having an end wall, a wire opening through said end wall, a wire extending into said socket through said wire opening, a contact on an end of said wire within said socket, an insulated disc on said wire immediately adjacent said contact, a first sealing washer on said wire intermediate said insulated disc and said end wall, a tubular bulb holder, said bulb holder having open ends and bulb securing means mounted therein for positioning a bulb in said bulb holder with a contact of the bulb projecting through one end thereof, cooperating thread means on said bulb holder and said socket for positioning said bulb holder in said socket, and a second sealing washer disposed intermediate said insulated disc and said bulb holder, said socket being a sealed part of a metal light housing, a ground wire connecting on said light housing, and a lens sealed to said metal light housing and cooperating therewith to form a sealed unit.
